United States Patent Office

Des. 186,958
Patented Dec. 29, 1959

186,958

SPECTACLE FRAME FRONT

Francis B. Neary, Rochester, N.Y., assignor, by mesne assignments, to Textron Inc., Providence, R.I., a corporation of Rhode Island

Application October 11, 1957, Serial No. 48,074

Term of patent 14 years

(Cl. D57—1)

FIG. 1.

FIG. 2.

FIG. 3.

FIG. 4.

Fig. 1 is a front elevational view of a spectacle frame front embodying my new design;

Fig. 2 is a top plan view thereof;

Fig. 3 is a rear elevational view thereof; and

Fig. 4 is a cross-sectional view thereof on an enlarged scale taken on the line 4—4 of Fig. 1, looking in the direction of the arrows.

I claim:

The ornamental design for a spectacle frame front, substantially as shown.
